GRINDING MACHINE

Harold L. Blood, Worcester, Mass., assignor to
The Heald Machine Company, Worcester,
Mass., a corporation of Massachusetts

Application April 13, 1932, Serial No. 604,988

17 Claims. (Cl. 51—50)

The present invention relates to grinding machines and in certain of its aspects is applicable to any of the various types of grinding machines. Its particular utility, however, is in connection with internal grinding machines for grinding the internal cylindrical or conical surfaces of sleeves, gears, bushings and like articles.

In the Guild and Burns grinding machine Patent No. 1,830,358, issued November 3, 1931, the grinding wheel is fed transversely at right angles to its axis toward the workpiece to procure successively deeper and deeper cuts in said workpiece until said workpiece reaches the finished size and at the end of the grinding operation the grinding wheel is automatically returned to the original position at the beginning of the grinding operation in order to position the grinding wheel for entry within the bore of the successive work piece without contacting therewith. In each grinding operation, the wheel is fed transversely from its original position into engagement with the workpiece at the same rate of speed at which it is fed after the wheel engages the workpiece and begins to cut into said workpiece. The time involved in the transverse feeding of the grinding wheel from its original position until it engages the surface of the workpiece, during which time no grinding action takes place, is entirely unproductive and thus the grinding operation on each workpiece involves more time than would be necessary if positive grinding began immediately upon entry of the wheel within the bore of the workpiece. It is accordingly the principal object of the present invention to provide for a relatively fast transverse movement of the grinding wheel toward the surface of the workpiece until the grinding wheel engages said workpiece with the rate of movement substantially diminished when the grinding wheel engages the surface of the workpiece.

The Taylor Patent No. 1,682,673 issued August 28, 1928, discloses a mechanism by which the rate of movement of the wheel against the surface of the work is diminished during the grinding operation under the control of the crossfeed mechanism for the grinding wheel and the Conradson Patent No. 1,534,302 discloses a different mechanism by which the rate of feeding movement may be varied during the grinding operation by entry of a gage within the bore of the partly ground workpiece. By reason of the variations in size of the workpieces before the grinding operation thereon, these mechanisms both of which operate mechanically when the workpiece is partly ground are unsatisfactory in reducing the rate of feeding movement of the grinding wheel just as said wheel engages the surface of the workpiece. Accordingly, a further object of the present invention is to provide for reduction of the rapid feeding movement of the grinding

wheel when said wheel engages the surface of the unfinished workpiece independently of the size of said unfinished workpiece.

In accordance with the present invention, the movement of the grinding wheel toward the surface of the workpiece is procured at a rapid rate until the wheel and work are in engagement when, by the energization of a light responsive element actuated by the sparks from the grinding wheel at the instant of contact, the rate of movement of the grinding wheel toward the workpiece is substantially diminished.

Other and further objects and advantages of the invention will more fully appear from the following description, taken in connection with the accompanying drawings, in which:—

Fig. 1 is a front elevation of a grinding machine embodying the invention.

Fig. 2 is a plan view of the grinding machine of Fig. 1.

Fig. 3 is an elevation of the crossfeed mechanism, parts being broken away.

Fig. 4 is a plan view of the crossfeed mechanism.

Fig. 5 is a diagrammatic view showing the relative position of the grinding wheel, the workpiece, and the light responsive element.

Fig. 6 is a rear elevation of a portion of the grinding machine showing the mechanism for the crossfeed retraction.

Fig. 7 is a wiring diagram.

Like reference characters refer to like parts in the different figures.

Referring first to Fig. 1, the machine provides the reciprocating table or carriage 1 ordinarily provided in internal grinding machines. Either the grinding wheel or the workpiece to be ground may be carried by the table 1, with the reciprocations of the latter utilized in either case to produce a relative traversing movement of the grinding wheel over the surface of the workpiece. In the construction shown, the table 1 carries a wheelhead 2 which supports the spindle 3 on which the grinding wheel 4 is mounted, and the work to be operated upon is held in a workhead 5, the latter carried by a bridge 6 which spans the slideways, not shown, provided for the back and forth movement of the table 1.

The back and forth movement of the table 1, to cause the grinding wheel to make the required traverse over the surface of the workpiece a may be imparted in any suitable manner as by the use of the fluid pressure mechanism forming the subject matter of the Heald and Guild Patent No. 1,582,468, granted April 27, 1926. It is sufficient to note for the purposes of the present application that the reciprocations of the table are controlled by the use of spaced adjustable dogs 7 and 8 mounted on the table 1 in a position to engage and move a reversing lever 9, the latter

during the grinding operation being located between the two dogs and being automatically engaged and actuated thereby.

The crossfeed movement between the workpiece and the grinding wheel to feed said grinding wheel at right angles to its axis against the surface of the workpiece is procured by the mechanism disclosed in the Taylor Patent No. 1,682,673. It is sufficient to note for the purposes of the 10 present application that the wheelhead 2 of the machine, which is mounted on a cross-slide 10, Fig. 2, is adapted to have a transverse movement on ways 10' provided by a bracket 11 mounted on the table 1. Movement of the cross-slide is 15 procured by rotation of a screw shaft 12, the latter engaging an internally threaded member secured to the cross-slide. The forward end of the screw shaft 12 carries a ratchet 13, and a pawl 14 pivotally mounted on an arm 15, the latter being 20 supported by a stud 16 on the cross-slide, is arranged to engage said ratchet to procure rotation of the shaft 12. The arm 15 carries a roller 17 which is adapted, at the end of each left hand longitudinal stroke of the table 1 while the grinding 25 wheel is in operative position relative to the work, to engage a stationary cam 18 carried by a longitudinal bar 20 attached to the bridge 6. When the roller 17 engages the cam 18, the arm 15 is rocked upwardly causing the pawl 14 to engage the ratchet wheel 13, thereby procuring a step-by-step clockwise rotation of the ratchet 30 wheel and accordingly of the screw shaft 12.

During the upward rocking movement of the arm 15, the pawl 14, which is normally held out 35 of engagement with the ratchet wheel 13 by the usual spring pressed plunger 21, is urged into engagement with said ratchet wheel, thereby procuring a clockwise movement of said ratchet wheel. To this end, a depending arm 22, pivotally mounted on a stud 23 on the cross-slide, carries, on the lower end thereof, an adjustable pin 24 in a position to engage the beveled surface 25 of the pawl 14 as it is moved upwardly to press said pawl against the ratchet wheel, said 40 pin 24 being adjustable in the arm 22 and being locked in adjusted position by a nut 26. The lower end of the arm 22 also carries an adjustable screw 27, the lower end of which, as shown in Fig. 3, engages a surface 28 of the bracket 11, said 45 screw 27 holding the pin 24 in proper position. The rate of crossfeed movement of the grinding wheel is determined by the position of the arm 22 and the pin 24 which are normally in the 50 position shown, and said pin, in accordance with its location, causes the pawl to procure greater or less angular rotation of the ratchet for each 55 upward movement of the pawl.

At the beginning of the grinding operation, the 60 grinding wheel is moved, from the inoperative position shown, into the bore of the workpiece by the fluid control disclosed in the above Head and Guild Patent No. 1,582,468, and the crossfeed movement is procured in response to the reciprocations over the surface of the workpiece, in the 65 manner above pointed out, until the workpiece is reduced to the predetermined finished size when, by suitable mechanism, as disclosed in the Taylor Patent No. 1,682,673, or in the Conradson Patent No. 1,534,302, above identified, the grinding 70 wheel is withdrawn from the workpiece and run out to the rest position shown to permit the finished workpiece to be replaced by an unfinished workpiece within the workhead.

Between successive grinding operations the 75 crossfeed movement is retracted to place the

grinding wheel in a position to enter the bore of an unfinished workpiece. To this end, the screw shaft 12 carries on the rearward end thereof of a ratchet wheel 28 which is engaged by a pawl 30, the latter being actuated at the end of a grinding operation, when the workpiece reaches the predetermined size, to procure a counterclockwise rotation of the screw shaft 12 (clockwise, as viewed from the rear, Fig. 6) to return the grinding wheel to the original position which it occupied at the beginning of the grinding operation. Referring now to Fig. 6, the pawl 30 is carried on the end of a bell crank lever 31 which is mounted for rotation on the shaft 12 and the other end of said lever 31 carries a roller 32 which engages a groove 33 in a horizontal bar 34, elevation of which, by fluid under pressure at the end of the grinding operation, rotates the bell crank lever 31 to procure turning movement of the screw shaft through the pawl 30. Said pawl 30 is held out of engagement with the ratchet wheel 28 during the crossfeed movement of the grinding wheel by a shield 35 carried by an arm 36 secured to the bracket 11, and extending between said pawl and the ratchet wheel when the bar 34 is in its lower position.

When the workpiece reaches the predetermined finished size, a bell crank lever 37 on the front of the machine is actuated counterclockwise through connections responsive to the turning movement of the crossfeed mechanism, as in the Taylor Patent No. 1,682,673, or responsive to entry of a gage within the bore of the workpiece, and the movement of the lever 37 procures withdrawal of the wheel from the workpiece into the rest position shown, and also procures the retraction of the crossfeed. A depending arm 38 of the bell crank lever 37 moves a valve 40 to provide fluid connection between a fluid pump, not shown, and the lower end of a cylinder 41 in which a piston is slidable, the latter carrying a piston rod 42 connected to the horizontal bar 34. Admission of fluid under pressure to the cylinder 41 urges the piston rod 42 upwardly, thereby elevating the horizontal bar 34 to turn the crossfeed screw 12 for retraction of the crossfeed. The repositioning of the grinding wheel or the insertion of an unfinished workpiece within the workhead releases the bell crank lever and permits it to return to its normal position shown, thereby moving the valve 40 to the left and providing fluid connection between the cylinder 41 and an exhaust connection, not shown, to permit the bar 34 under its own weight to return to its lower position with the pawl 30 supported out of engagement with the ratchet 28 by the shield 35.

The above described mechanism, of itself, forms no part of the present invention which latter involves the attainment in connection with such or similar grinding machine instrumentalities of the novel and useful objects and results hereinbefore set forth. In accordance with the present invention, as the grinding wheel is moved into operative position within the bore of the workpiece *a*, Fig. 5, by movement of the table 1 toward the left, said grinding wheel occupies substantially the position shown in the dotted lines, in which position the surface of the grinding wheel is entirely out of contact with the workpiece. As the table 1 is reciprocated to procure a traversing movement of the grinding wheel over the surface of the workpiece, the pawl 14 is actuated by the cam 18, as above pointed out, and the ratchet wheel 13 is rotated to procure a rapid crossfeed movement of the grinding wheel toward the sur- 150

face of the workpiece to diminish the unproductive period of the grinding operation while the grinding wheel is not in contact with the workpiece.

- 5 As soon as the grinding wheel engages the surface of the workpiece, the crossfeed movement is diminished to the normal crossfeed rate for the grinding operation, such reduction in crossfeed rate being procured independently of the relative position of the cross-slide on the table 1. To this end, as the grinding wheel moves into contact with the workpiece, the incandescent sparks caused by the contact of the wheel with the work illuminate a photo-electric cell which 15 procures a decrease in the rate of crossfeed movement. Referring first to Fig. 3, the bracket 11 supports a bell crank lever 43 pivotally mounted on a pin 44 with one end 45 of the lever in a position to engage beneath the end of the adjusting 20 screw 27 when said lever 43 is rocked counterclockwise. The opposite end 46 of the bell crank lever 43 is connected to the armature 47 of a solenoid 48 mounted on the bracket 11, and said solenoid, when energized, procures counterclockwise 25 rotation of the lever 43 to move the end 45 of said lever into position beneath the end of the screw 27 and spacing the pin 24 away from the ratchet wheel 13 so that the pawl 14 engages said ratchet wheel 13 during a shorter portion of its upward 30 movement, and the ratchet wheel is accordingly turned through a smaller angle.

Referring now to Fig. 7, the photo-electric cell or other light responsive instrumentality in a shield 50, which instrumentality is activated by the incandescent sparks from the grinding wheel, is connected by leads 51 and 52 to a relay mechanism 53 which is operated in response to activation of the photo-electric cell to close a switch connecting a generator 54 to the solenoid 48. One 40 terminal of the generator 54 is connected by a lead 55 to a ground 56 and the other terminal of the generator is connected by a lead 57 to the normally open switch in the relay box 53, the other terminal of said switch being connected by a lead 58 to the solenoid 48 which latter is connected by a lead 60 to a ground. As best shown in Fig. 2, the shield 50 in which the photo-electric cell is mounted is carried by a bracket 61 secured to a hood 62 which extends over the workhead, and the opening 63 in the shell 50 is directed toward the incandescent sparks so that the light therefrom may activate the light responsive instrumentality therein to diminish the rate of crossfeed movement.

55 At the end of the grinding operation when the grinding wheel is withdrawn from the workpiece, the switch in the relay box 53 which has remained closed during the grinding operation is opened and the solenoid 48 is deenergized. A spring 64, 60 which normally tends to rock the bell crank lever 43 clockwise, returns said lever to the position shown in Fig. 3, so that the arm 22 is lowered in readiness for a rapid crossfeed movement during a subsequent grinding operation.

65 In the operation of the machine, the grinding wheel is moved axially from the rest position shown in Fig. 1 into the bore of the workpiece substantially into the position indicated by the dotted lines of Fig. 5 where it is reciprocated axially to procure a traversing movement of the grinding wheel over the workpiece. The axial reciprocation procures a rapid crossfeed movement of the grinding wheel perpendicularly to its axis to procure a cutting action between said wheel and workpiece. As the grinding wheel moves into contact

with the workpiece, incandescent sparks are given off from the wheel, thereby energizing the light responsive element to elevate the arm 22 to diminish the rate of crossfeed movement. As the grinding operation continues, the workpiece is eventually reduced to the predetermined size at which time the grinding wheel is withdrawn axially from the workpiece to the rest position shown and at the same time the crossfeed movement perpendicular to the axis of the grinding wheel is retracted, thereby returning the grinding wheel to the position shown in Fig. 1 in readiness for a subsequent grinding operation.

80 From the foregoing, it will be apparent that the feeding movement of the wheel against the workpiece is procured at a plurality of rates of feed. During the initial movement of the grinding wheel toward the workpiece while said members are still out of contact, the crossfeed movement is rapid to diminish the unproductive period of the grinding operation. Engagement of the grinding wheel with the workpiece produces incandescent sparks which activate a light responsive element for diminishing the rate of feeding movement to a suitable grinding rate. Obviously, the rate of crossfeed subsequently may be again diminished as disclosed in the Conradson Patent No. 1,534,302, above noted.

90 95 100 105 110 115 120 125 130 135 140 145 150

From the foregoing, it will be apparent that the feeding movement of the wheel against the workpiece is procured at a plurality of rates of feed. During the initial movement of the grinding wheel toward the workpiece while said members are still out of contact, the crossfeed movement is rapid to diminish the unproductive period of the grinding operation. Engagement of the grinding wheel with the workpiece produces incandescent sparks which activate a light responsive element for diminishing the rate of feeding movement to a suitable grinding rate. Obviously, the rate of crossfeed subsequently may be again diminished as disclosed in the Conradson Patent No. 1,534,302, above noted.

The term "grinding operation" has been used throughout the specification to include the movements of the machine from the rest position shown at which time the grinding wheel is out of contact with the workpiece and has been withdrawn from the bore thereof into the bore of the workpiece and through the entire operation until the workpiece is reduced to the finished size and is withdrawn from said workpiece, thereby including the unproductive period between the beginning of the crossfeed movement and the time of engagement of the grinding wheel with the workpiece.

I claim:

1. In a grinding machine, a grinding wheel and a workholding member supporting a workpiece, feeding mechanism to cause the grinding wheel and workpiece to move toward each other to obtain and maintain grinding contact, and means responsive to engagement between the grinding wheel and the workpiece for diminishing the rate of movement when said grinding wheel engages the workpiece independently of the original size of the workpiece.

120 125 130 135 140 145 150

2. In a grinding machine, a grinding wheel and a workholding member supporting a workpiece, feeding mechanism to cause the grinding wheel and workpiece to move toward each other to obtain and maintain grinding contact, and means for diminishing the rate of movement when said grinding wheel engages said workpiece, said last means involving a light responsive member energized by the sparks from the grinding wheel.

3. In a grinding machine, a grinding wheel and a workholding member supporting a workpiece, means for feeding the grinding wheel against the surface of the workpiece, and means responsive to engagement between the grinding wheel and the workpiece for diminishing the rate of feeding movement when the grinding wheel engages the workpiece independently of the size of the workpiece.

140 145 150

4. In a grinding machine, a grinding wheel and a workholding member supporting a workpiece, means for feeding the grinding wheel against the surface of the workpiece, and means for diminishing the rate of feed when the grinding wheel en-

- gages the workpiece, said last means involving a light responsive member energized by the sparks from the grinding wheel.
5. In a grinding machine, a grinding wheel and a workholding member supporting a workpiece, means for procuring a feeding movement of the wheel toward and against the surface of the workpiece, and means responsive to engagement of the grinding wheel with the workpiece for procuring 10 a change in the rate of feeding movement, said last means involving a light responsive member.
6. In a grinding machine, a grinding wheel and a workholding member supporting a workpiece, means for procuring a rapid feeding movement of 15 the wheel toward and against the surface of the workpiece, and means responsive to engagement of the grinding wheel with the workpiece to diminish the rate of feeding movement, said last-mentioned means comprising a light responsive 20 member energized by the illumination of the sparks from the grinding wheel.
7. In a grinding machine, a grinding wheel and a workholding member supporting a workpiece, feeding mechanism to cause the grinding wheel 25 and workpiece to move toward each other to obtain and maintain grinding contact, and means for diminishing the rate of movement when said grinding wheel engages said workpiece, said last means involving a light responsive member energized by the sparks from the grinding wheel, said light responsive member operating independently 30 of the size of the unfinished workpiece.
8. In a grinding machine, a grinding wheel and a workholding member supporting a workpiece, 35 means to procure a crossfeed movement of the grinding wheel against the surface of the workpiece, and light responsive means energized by the illumination of the sparks from the grinding wheel for diminishing the rate of crossfeed movement as the grinding wheel engages the workpiece.
9. In a grinding machine adapted for the successive reduction of a plurality of workpieces to a predetermined size, a grinding wheel and a workholding member supporting a workpiece, 45 means to procure a grinding operation on a workpiece, said grinding operation involving a crossfeed movement of said grinding wheel relative to the workpiece, means operative between successive grinding operations to retract said crossfeed 50 whereby said grinding wheel is out of engagement with the successive workpiece at the beginning of the successive grinding operation, and means operable during the grinding operation when the grinding wheel engages the workpiece and in response to engagement therebetween for diminishing 55 the rate of crossfeed movement independently of the size of the workpiece.
10. In a grinding machine adapted for the successive reduction of a plurality of workpieces 60 to a predetermined size, a grinding wheel and a workholding member supporting a workpiece, means to procure a grinding operation on a workpiece, said grinding operation involving a crossfeed movement of said grinding wheel relative 65 to the workpiece, means operative between successive grinding operations to retract said crossfeed whereby said grinding wheel is out of engagement with the successive workpiece at the beginning of the successive grinding operation, and 70 light responsive means operable during the grinding operation and energized by the illumination
- of the sparks from the grinding wheel as said wheel engages the workpiece for diminishing the rate of crossfeed movement.
11. In a grinding machine, a grinding wheel and a workholding member supporting a workpiece, means for procuring a crossfeed movement of the grinding wheel relative to the surface of the workpiece during the grinding operation, said grinding wheel being out of engagement with the workpiece at the beginning of the grinding operation, and light responsive means to vary the rate of crossfeed movement in response to engagement of said wheel with the workpiece. 80
12. In a grinding machine, a grinding wheel and a workholding member supporting a workpiece, means to procure a grinding operation on the workpiece, the grinding wheel being out of engagement with the workpiece at the beginning of the grinding operation, and light responsive means energized by the illumination of the sparks from the grinding wheel when said grinding wheel 85 engages the workpiece for procuring a change in the grinding operation.
13. In a grinding machine, a grinding wheel and a workholding member supporting a workpiece, means for feeding the grinding wheel against the surface of the workpiece, and means for diminishing the rate of feed when the grinding wheel engages the workpiece, said last means involving a light responsive member. 90
14. In a grinding machine adapted for the successive reduction of a plurality of workpieces to a predetermined size, a grinding wheel and a workholding member supporting a workpiece, means to procure a grinding operation on a workpiece, said grinding operation involving a crossfeed movement of said grinding wheel relative to the workpiece, means operative between successive grinding operations to retract said crossfeed whereby said grinding wheel is out of engagement with the successive workpiece at the beginning of the successive grinding operation, and light responsive means operable during the grinding operation and energized by the illumination of the sparks from the grinding wheel 100 for controlling the rate of crossfeed movement. 105
15. In a grinding machine, a grinding wheel and a workholding member supporting a workpiece, means to procure a grinding operation on the workpiece, and light responsive means energized by the illumination of the sparks from the grinding wheel for procuring a change in the grinding operation. 110
16. In a grinding machine, a grinding wheel and a workholding member supporting a workpiece, means to procure a grinding operation on the workpiece, the grinding wheel being out of engagement of the workpiece at the beginning of the grinding operation, and light responsive 115 means energized by the engagement of said grinding wheel with the workpiece for procuring a change in the grinding operation.
17. In a grinding machine, a grinding wheel and a workholding member supporting a workpiece, means to procure a grinding operation on the workpiece, and light responsive means controlled by the illumination of the sparks from the grinding wheel for controlling the progress of the grinding operation. 120

HAROLD L. BLOOD.
